CLAIM

The ornamental design for an electrical connector, as shown and described.

DESCRIPTION

FIG. 1 is a front perspective view of an electrical connector showing our new design, the contact being shown in broken lines for illustrative purposes only;

FIG. 2 is a top plan view thereof;

FIG. 3 is a left side view thereof with the right side now shown being a mirror image thereof;

FIG. 4 is a front end view thereof;

FIG. 5 is a rear end view thereof; and

FIG. 6 is a bottom view thereof.
